(57) **CLAIM**

The ornamental design for a collapsible suitcase, as shown and described.

DESCRIPTION

FIG. 1 is a front perspective view of the collapsible suitcase showing our new design;

FIG. 2 is a front perspective view thereof, showing the suitcase in a collapsed state;

FIG. 3 is a front elevation view thereof;

FIG. 4 is a rear elevation view thereof;

FIG. 5 is a left side view thereof;

FIG. 6 is a right side view thereof;

FIG. 7 is a top view thereof; and,

FIG. 8 is a bottom view thereof.

The broken lines illustrate portions of the collapsible suitcase and form no part of the claimed design.
